UNITED STATES PATENT OFFICE.

SAMUEL H. DAVIS, OF ALFRED, NEW YORK.

DESIGN FOR AN ELECTRIC-LIGHT FIXTURE.

SPECIFICATION forming part of Design No. 26,034, dated September 15, 1896.

Application filed February 3, 1896. Serial No. 577,936. Term of patent 14 years.

To all whom it may concern:

Be it known that I, SAMUEL H. DAVIS, a citizen of the United States, residing at Alfred, in the county of Allegheny, in the State of New York, have invented and produced a new and original Design for Globes and Brackets, of which the following is a specification.

Referring to the accompanying drawings, which form part of this specification, Figure 1 is a perspective view of the bracket and globe, and Fig. 2 is a sectional view on the line $x-x$ of Fig. 1.

1 represents my design of indicating-globe for electric or other lamps, which is made in the shape of a human hand, having the index-finger in the attitude of pointing, as clearly shown.

In cross-section the globe is approximately circular, with an irregular scalloped effect in one side. The rear portion of the globe tapers

slightly to correspond with a wrist and terminates in a curved flange, the inner wall of the flange having a curve of the same general contour as the outer wall. This globe is secured to a bracket consisting of a straight rear end, from which leads a hollow arm 2, at the top, and a curved brace 3, which extends to the rear end of the arm, said arm being enlarged and ending in a semi-oval extension where the globe joins it.

What I claim is—

The design for a globe and bracket substantially as herein described and shown.

In testimony whereof I have hereunto affixed my signature in the presence of two subscribing witnesses.

SAMUEL H. DAVIS.
